UNITED STATES PATENT OFFICE.

JOHN L. OLSON, OF WARREN, MINNESOTA.

DITCHING-PLOW.

SPECIFICATION forming part of Letters Patent No. 377,837, dated February 14, 1888.

Application filed September 30, 1887. Serial No. 251,105. (No model.)

To all whom it may concern:

Be it known that I, JOHN L. OLSON, of Warren, in the county of Marshall and State of Minnesota, have invented certain new and useful Improvements in Ditching-Plows; and I do hereby declare the following to be a full, clear, and exact description of the invention, such as will enable others skilled in the art to which it pertains to make and use the same.

10 My invention relates to ditching-plows, the object being to provide a device of this character that will be simple in construction and effective in operation.

The invention consists in the details of construction and combinations of parts hereinafter fully described, and pointed out in the claim.

In the drawings, Figure 1 is a view taken from the side opposite the plow. Fig. 2 is a view taken from the plow side of the machine. 20 Fig. 3 is a plan view, and Fig. 4 is a view taken from the rear end of the machine.

A' represent the draft-wheels rigidly mounted upon the ends of the axle B.

The frame consists of the bars C C', connected together near their front and rear ends by the cross-bars C² C³, respectively. Between the front ends of the bars C C' the draft is attached, and upon the cross-bar C² the seat c is arranged. About midway the ends of the bars 30 C C' the depending arms D D are secured. The depending arms D D are perforated near their lower ends, and the axle B is passed loosely through said perforations. It will thus be seen that the frame is capable of a swinging movement in relation to the wheels and axle.

Upon the cross-bar C², just to the left of the bar C, a supporting-bracket, E, is secured. The bracket E projects rearwardly at first and is then turned downwardly, the lower portion 40 of said bracket being provided with a slot, E'.

The beam F is arranged between the wheels A A' and adjacent to the wheel A. The forward end of the beam F is provided with the caster-wheel f, and upon its rear end a plow, F', of ordinary construction, is attached. A pin, I, having a head, i, is passed loosely through the slot E' and is secured in the rear end of the beam F. An upright, G, is secured upon the beam F, and it passes just in the rear 50 of the axle B. At its upper end it is provided

with a set of perforations, g, and in one of these a lever, G', is secured by passing a pin through the said lever and perforation. The lever G' is pivoted upon a post, g², and its other end is arranged to engage a set of notches, g³, in the post G². Upon the beam F, forward of the upright G and adjacent to the axle B, a guide, H, is arranged. It will thus be seen that the height of the plow F' may be regulated so that it will either make a furrow or merely pass 60 over the surface of the ground; and it will further be seen, by reason of the loose joint between the beam F and the bracket E, that no matter how uneven the surface of the ground may be, thus causing a jolting of the frame and 65 sudden rising and falling of the wheels, the plow will move along in a horizontal plane.

To the outer side of the wheel A', and upon the axle B, a bevel gear-wheel, M, is secured.

Depending from the bar C' and cross-bar C³ 70 are the braces N N', the brace N being arranged obliquely and the brace N' vertically. A shaft, O, is supported at its rear end in the brace N and passes through the brace N', and its forward end is supported in a hub, O', mounted 75 loosely upon the end of the axle B. Near the forward end of the shaft O a bevel-gear, P, is rigidly secured, and the gear P meshes with the gear M. Loosely secured to the shaft O are the side pieces, p p. The said side pieces 80 are secured together by suitable means, and at their lower ends a roller, R, is arranged. Upon this frame and around the shaft O and roller R an endless belt or carrier, R', is adjusted. The lower end of the endless carrier is arranged 85 adjacent to the mold-board of the plow, and is adapted to convey away the dirt thrown upon it by the plow by reason of the shaft O, provided upon its end with the gear P, which meshes with the gear M upon the axle B. From 90 the foregoing it will be seen that when the machine moves, the shaft O will revolve and thus revolve the carrier R'. The dirt is deposited quite a distance to the side of the ditch.

Upon the frame of the device a lever, T, is 95 pivoted upon a post, t, and one end of said lever is connected to the lower end of the carrier S by means of the chain or other suitable connection u and frame v', while the other end is adjusted so as to engage the notches in a 100

post, T'. From the foregoing it will be seen that the height of the carrier in relation to the plow F' can be regulated.

Having fully described my invention, what I claim as new, and desire to secure by Letters Patent, is—

In a ditching-plow, the combination, with the frame, depending arms D, and axle B, provided with suitable carrying-wheels, of a beam, F, having a caster-wheel and plow, and upright G, secured to said beam and pivoted to a lever, G', which is arranged upon a post, g², said up-

right G, and a guide, H, embracing the axle, and a headed pin, J, secured to the rear end of the beam and adapted to work in a slot, E', formed in a bracket, E, substantially as described.

In testimony whereof I have signed this specification in the presence of two subscribing witnesses.

JOHN L. OLSON.
